UNITED STATES PATENT OFFICE.

TOBIAS MILLER, OF NEW YORK, N. Y., ASSIGNOR OF ONE-HALF TO LOUIS P. WHITEMAN, OF SAME PLACE.

DESIGN FOR A TOE-CLIP.

SPECIFICATION forming part of Design No. 27,900, dated November 23, 1897.

Application filed September 30, 1897. Serial No. 653,653. Term of patent 3½ years.

To all whom it may concern:

Be it known that I, TOBIAS MILLER, a citizen of the United States, residing at New York, in the county of New York and State of New York, have invented and produced a new and original Design for a Toe-Clip; and I do declare the following to be a full, clear, and exact description of the same, reference being had to the accompanying drawings, forming a part thereof.

The leading feature of the design consists in the novel shape and configuration of the toe-clip, as shown in the accompanying drawings, in which—

Figure 1 is a top view of a toe-clip for bicycles bearing and incorporating my design. Fig. 2 is a bottom view of same. Fig. 3 is an edge view of same, and Fig. 4 is a detached section of a portion of same on the dotted line 4 4 of Fig. 3.

In the drawings, A A indicate the two side members of the clip, said members converging toward one another at their ends and on curved lines and having the raised ribs B, which follow the curvature of the edges of 25 said members.

At the top of the clip the members A A are joined together by the bar C, and thence merge into the portion D of the clip, which portion D is of the outline shown and contains the 30 circular central panel E and openings F, said openings being of ornamental outline and disposed around said panel E, as shown in Fig. 1.

The members A A at the bottom of the clip merge into one another, as at G, and thence 35 the bottom of the clip turns downward at right angles, forming an ear H, having a screw-hole I. At about the central portion of the bottom of the clip is the ornamental cross-bar J.

What I claim is—

The design for a toe-clip, as shown and described.

In testimony whereof I affix my signature in presence of two witnesses.

TOBIAS MILLER.
